UNITED STATES PATENT OFFICE.

JULIUS M. GERMANSON, OF MILWAUKEE, WISCONSIN, ASSIGNOR TO WESTERN MALLEABLE AND GREY IRON MANUFACTURING COMPANY, OF MILWAUKEE, WISCONSIN, A CORPORATION OF WISCONSIN.

DESIGN FOR A CHAIR-SEAT SPIDER.

SPECIFICATION forming part of Design No. 35,345, dated November 26, 1901.

Application filed October 16, 1901. Serial No. 78,899. Term of patent 7 years.

To all whom it may concern:

Be it known that I, JULIUS M. GERMANSON, residing at Milwaukee, in the county of Milwaukee and State of Wisconsin, have invented and produced a new and original Design for a Chair-Seat Spider, of which the following is a description, reference being had to the accompanying drawings, which are a part of this specification.

material feature of my design consists of a chair-seat spider having the two longitudinal arms A A, end members B B, said end members B connecting the extremities of the longitudinal arms A, and an intermediate transverse piece C, the whole producing a spider of the general form of a rectangular frame having an intermediate transverse piece which forms two rectangular openings.

Having described my invention, what I claim as new, and desire to secure by Letters Patent, is—

The design for a chair-seat spider, as herein shown and described.

In testimony whereof I affix my signature in presence of two witnesses.

JULIUS M. GERMANSON.

Witnesses:

ARTHUR L. MORSELL,
ANNA V. FAUST.

10 My invention has relation to a new and original design for a chair-seat spider, more especially of the type of chair-seat spiders used in connection with office or so-called "revolving chairs."

15 I have illustrated the design in the accompanying drawings, in which—

Figure 1 is a plan view of a spider, showing my new design. Fig. 2 is a longitudinal section thereof, and Fig. 3 is an end view.

20 As shown in the drawings, the leading or
